UNITED STATES PATENT OFFICE.

MAXIM ZAVARKIN, OF EAST BRIMFIELD, MASSACHUSETTS.

CONCRETE TIE.

1,269,894.

Specification of Letters Patent. Patented June 18, 1918.

Application filed January 2, 1918. Serial No. 209,932.

To all whom it may concern:

Be it known that I, MAXIM ZAVARKIN, a citizen of Russia, resident of East Brimfield, county of Hampden, and State of 5 Massachusetts, have invented certain new and useful Improvements in Concrete Ties, of which the following is a specification.

This invention relates to improvements in railroad ties and particularly to those constructed principally of concrete.

The principal object of the invention is to provide a tie relatively light, exceptionally strong and of extreme durability.

A further object is to provide a tie or 15 sleeper formed of concrete molded into shape, whereby the cost of construction is reduced, and finally, to provide in the ends of the tie, metallic inserts for receiving rail holding devices, such inserts being connected 20 by reinforcing rods passing longitudinally through the lower side of the tie.

These and other like objects are attained by the novel construction and combination of parts hereinafter described and shown 25 in the accompanying drawing, forming a material part of this specification, and in which:—

Figure 1 is a top plan view of a tie made in accordance with the invention, parts being shown in section in order to show the 30 interior construction.

Fig. 2 is a side view of the same.

Fig. 3 is an enlarged transverse sectional view taken on line 3—3 of Fig. 2.

Fig. 4 is a perspective view showing one 35 of the inserts, and securing elements embedded in the tie, and

Fig. 5 is a side elevational view showing a modified form of insert.

The tie, as shown in Figs. 1 and 2 is substantially rectangular, comprising a pair of oppositely disposed spaced heads 10 integrally connected by a central element 11, narrower than the heads which are formed 40 with exterior beveled surfaces 12, thereby rendering it easy to raise and remove the same from the ground by a bar.

In the heads 10 are pairs of metallic reinforcing inserts, the pairs being spaced to 45 suit the distance between the rails, and the members of each pair so spaced that the bolts, entered therein, engage upon either side of the rail flange.

The upper element 14 of the insert is 50 set below the upper surface of the tie, parallel therewith and is provided with a plu-

rality of threaded openings 15 for bolts, screws or like securing means.

Engaged with the ends of the upper element 14 are angularly disposed braces 16, 60 joined at their lower end by a lower element 17 and having therebetween a center bar 18, forming through spaces 19 which obviously will become filled with cement in the process of molding, serving to bind and 65 hold the inserts solidly within the heads of the tie. These inserts are further held in the material of the tie by means of rods 20 fitted to openings 21 formed in the lower element 17 of the insert, the entire structure being thus firmly bound together.

The openings 15 in the top of the inserts register with openings 22, in the top of the tie through which securing bolts may be entered.

In Fig. 5 is shown a modification of insert, the same being formed in separate sections, the upper of which has an element 25 from which depend arms 26 and a central stem 27, the latter of which is fitted between 80 guides 28 formed with the bottom element 30 of the lower insert section and is also provided with openings 31 for receiving the binding rods 20, threaded screw holes passing through the top element 25 in the manner before described.

The depending arms 26 of the upper section are formed with serrations 33, engageable with similar serrations 34, formed in the upper arms 35 of the lower section 30, 90 so that when the two sections are in intimate relation, any weight which may be placed upon the upper section 25 will be transmitted by the serrations to the lower section in an obvious manner, it being evident that the parts must be assembled before pouring the cement.

From the foregoing it will be seen that a strong and durable form of tie has been disclosed.

Having thus described my invention, what I claim as new and desire to secure by Letters Patent, is

1. In a concrete tie, the combination with a rigid body having enlarged heads receptive of track-rails and an integrally formed connecting element therebetween, of beveled surfaces formed at the ends of said tie, metallic inserts arranged in pairs at the ends of said tie, and a pair of tie rods extending between said inserts embedded in the concrete.

2. In a concrete tie, the combination with an elongated body suited to receive track-rails, of spaced pairs of reinforcing metallic inserts near the ends of said body, said reinforcing inserts being comprised of two separate sections, the upper section having a central stem, a pair of upright guides formed with the lower section receptive of said stem and pairs of integral rigid arms formed with each section on adjacent portions, and interengaging corrugations on the contracting surfaces of said arms.
3. In a concrete tie, the combination with the body thereof, of a T shaped upper element having angularly disposed depending side arms, a lower element having outwardly extending arms, a plurality of corrugations formed upon the adjacent surfaces of all of said arms, and a pair of guides formed on said lower element adapted to make contact with the central stem of said T element.
4. In combination, a rigid body composed of two sections, one section having oppositely-inclined sides formed upon their inner edges with corrugations, an integral pair of central upwardly-extending portions, a second rigid body formed with oppositely-inclined sides formed with corrugations upon their outer edges engaging adjustably the corrugations on the first body, and having a depending central arm slidably mounted between the pair of upwardly-extending portions.

In testimony whereof I have affixed my signature.

MAXIM ZAVARKIN.
